UNITED STATES PATENT OFFICE.

ARTHUR G. ZIMMER, OF EAST ORANGE, NEW JERSEY.

METHOD FOR MANUFACTURING IMITATION GOLD-LEAF.

1,234,250.

Specification of Letters Patent. Patented July 24, 1917.

Application filed October 18, 1915. Serial No. 56,575.

To all whom it may concern:

Be it known that I, ARTHUR G. ZIMMER, a citizen of the United States of America, and a resident of East Orange, in the county of Essex and State of New Jersey, have invented certain new and useful Improvements in Methods for Manufacturing Imitation Gold-Leaf, of which the following is a specification.

- 10 The present invention relates to improvements in methods and apparatus for manufacturing imitation gold leaf, and has for its object to provide such means whereby a superior quality of imitation gold leaf may 15 be produced, resembling more closely real gold leaf and possessing strength, durability, luster and other advantageous qualities which will render it commercially desirable. Another object is to provide such 20 means by which the thickness of the leaf may be regulated as desired, and by which the leaf will have a uniform thickness throughout.

With these and other objects in view, my 25 invention is hereinafter more fully described with reference to the accompanying drawings and will be finally pointed out in the claims.

In the accompanying drawings,

30 Figure 1 is a perspective view of my improved apparatus in operation;

Fig. 2 is a longitudinal sectional view thereof;

Fig. 3 is a longitudinal sectional view of 35 a slightly modified form of construction;

Figs. 4 to 8 show various modified constructions for varying the thickness of the leaf;

Fig. 9 is a side elevation of a still further modified form of construction;

Fig. 10 is a side view of a still further modified form; and

Fig. 11 is a cross-sectional view thereof.

Similar reference characters indicate corresponding parts throughout the several figures of the drawings.

Referring to the drawings and more particularly to Fig. 1 thereof, the liquid 10 or other suitable material from which the imitation gold leaf is formed as a mixture of collodion, alcohol, ether and bronze in suitable proportions, is placed upon the bed or plate 11, which has a very smooth and highly polished surface, which may be produced in any convenient manner, such for

instance as nickel plating or the like. At each side there are provided grooves 12 and 13, which are inclined downwardly toward a trough 14 provided at one end of the plate, and which receives and guides the surplus 60 material to the said trough, whereupon it may be used again. At the opposite end of the plate 11, a retaining wall 15 is provided, which prevents the liquid running off at the rear. The outer edges of the plate beyond 65 the grooves 12 and 13 are a trifle higher, as at 16 and 17, than the bed of the plate, which difference corresponds to the thickness of the leaf to be produced.

A roller 18 also having a very highly 70 polished surface is drawn across the plate, the ends of the same resting on the sides 16 and 17 of the plate in such manner that the intermediate portion is spaced from the bed of the plate very slightly. This space, as 75 above pointed out, corresponds to the thickness of the sheet to be produced, and in drawing the roller over the plate the liquid is spread into a smooth unbroken sheet of a corresponding thickness. The roller may be 80 drawn over the plate simply once, or if desired, may be drawn back and forth several times, after which it is removed and the moisture is allowed to evaporate from the material, whereupon the sheet may be readily peeled from the plate.

In Fig. 3, I have shown a slightly modified form of construction, in which a squeegee 20, also having a highly polished surface, is employed for spreading, and gag- 90 ing the thickness of the material from which the leaf is formed. The instrument is operated in a similar manner to the roller.

In Fig. 4, the space between the roller and the plate is regulated by a strip of paper, 95 metal or other suitable material 21, secured along the sides of the plate.

In the form shown in Fig. 5, the ends of the roller are slightly enlarged, as at 22, to produce the desired space between the roller 100 and the plate.

In Fig. 6, the plate is disposed within a holder 23, and screws 24 support the same in spaced relation with the squeegee, which is provided at the ends with recesses 25, which 105 engage the sides of the bed and provide a guide for the same. By adjustment of the screw, the plate may be raised or lowered as desired.

In the form shown in Fig. 7, the plate is 110

provided at each side with a ledge 26, which is engaged by a cutout portion 27 of the squeegee, and a set screw 28 in the squeegee holds the same in the proper spaced relation 5 with respect to the plate.

In Fig. 8, I have shown the squeegee provided at the sides with handle portions 29 to facilitate the operation of the same.

In the construction illustrated in Fig. 9, I 10 have provided a plate which is movable longitudinally upon a rack 30 by means of gears 31 and mounted above the same upon a stationary support 32 is provided a squeegee 33, the ends of which engage the 15 raised sides 34 of the plate to space the squeegee from the plate. This space may be regulated by raising and lowering the squeegee with respect to the plate by means of a set screw 35.

20 In Figs. 10 and 11, I have shown a still further modified form of construction for regulating the thickness of the leaf. This consists of stationary strips 36 provided at the sides of the plate, above which are arranged on guide posts 37 and 38 movable strips or bars 39, which constitute the rests for the ends of the squeegee or roller. These 25 upper movable strips are supported on set screws 40 and 41 provided in the stationary strips, and by movement of the same the upper strips may be raised or lowered as 30 desired.

With the use of my improved construction, a very superior form of imitation gold 35 leaf may be produced, which will not tar-

nish, is very durable, and lends itself readily to the uses intended.

I have illustrated preferred and satisfactory forms of my invention, but it is obvious that changes may be made therein 40 within the spirit and scope thereof, as defined in the appended claims.

I claim:

1. An improved method of producing imitation metallic leaf, which consists in subjecting the material from which the imitation gold leaf is formed, to the action of two highly polished metallic surfaces, one moved continuously in respect to the other, with the material therebetween, for spreading 45 the material to a metallic leaf on one of the surfaces, and allowing it to dry thereon to form a leaf.

2. An improved method of producing imitation metallic leaf, which consists in placing the material from which the imitation gold leaf is formed, upon a highly polished flat surface, and then subjecting the material to the action of a highly polished surface passing over the material between the 50 polished surfaces, for spreading the material on the flat surface in a thin layer and allowing it to dry, to form a metallic leaf.

In testimony, that I claim the foregoing as my invention, I have signed my name in 55 presence of two subscribing witnesses.

ARTHUR G. ZIMMER.
